C. C. WHITE

DISAPPEARING BED

Original Filed Dec. 19, 1919

Fig. 1.

Fig. 2.

UNITED STATES PATENT OFFICE.

CHARLES C. WHITE, OF NEW YORK, N. Y.

DISAPPEARING BED.

Original application filed December 19, 1919, Serial No. 346,128. Divided and this application filed July 17, 1924. Serial No. 726,563.

To all whom it may concern:

Be it known that I, CHARLES C. WHITE, a citizen of the United States, and a resident of New York, in the county of New York, 5 and State of New York, have invented certain new and useful Improvements in Disappearing Beds, of which the following is a full, clear, and exact description.

The invention relates to disappearing 10 beds.

The present application is a division of that filed by me December 19, 1919, for disappearing beds, Serial Number 346,128.

In hotels and apartments in which disappearing beds are used, it is desirable to utilize the space in the bed compartment as a dressing room as well as a storage compartment for the beds, and the primary object of the present invention is to provide 15 a structure which is adapted to hold a plurality of beds with provision for access to the compartment, both when the beds are disposed therein or in the room, so that the compartment will always be available as 20 a dressing room.

The invention consists in the several novel features hereinafter set forth and more particularly defined by claims at the conclusion hereof.

30 In the drawings: Fig. 1 is a front elevation of a structure embodying the invention, the beds being shown in the closet. Fig. 2 is a horizontal section on line 2—2 of Fig. 1. Fig. 3 is a vertical section on line 3—3 of Fig. 2. Fig. 4 is a detail perspective, showing the manner of removably securing the beds to the doors.

A closet or recess 8, designed to contain a plurality of beds with sufficient space between them for use as a dressing room or the like, has a back-wall 10 and side walls 9 joining a partition or wall 11^a of a room 11. The front of the closet or compartment communicates with the room 11 and the opening between them is adapted to be closed by two doors 12, each of which is centrally pivoted, as at 13, and an intermediate or central door 14, which is pivoted at 15. These three doors form a complete 45 closure for the front of the closet. One of the doors 12 is provided with a pair of brackets 18 and screws 20, for securing the head-frame of either a single or double bed to said door. The other door 12 is provided with a similar bracket 18 and screw 50

20 for removably securing the head-frame of a single bed thereon.

The folding bed illustrated comprises a head-frame 17 and a cross-rail 17^a, a bed-frame 16 having a pivotal and slidably connection with the corner posts and links 16^a, of the construction more fully set forth in an application filed by me September 23, 1921, Serial No. 502,699. This bed construction exemplifies one which can be 60 swung into a vertical plane and to a horizontal operative position when it has been withdrawn from the closet.

Each door 12 being centrally pivoted, permits the bed thereon to be swung through an 70 arc of 180° so that the bed thereon may be disposed in the compartment or closet or in the living room 11. The intermediate or central door 14 can be opened when either one or both of the beds are in the closet or 75 in the living room, so that the closet may be used as a dressing room to which access can be obtained, either while the beds are in their operative position or while they are in the closet.

In some instances, it is desirable to produce additional sleeping capacity by providing a double bed in lieu of a single bed. This can be done by mounting the head-frame of the double bed as indicated by 80 dotted lines in Fig. 2. The intermediate door 14 is pivoted adjacent one of its edges. When additional sleeping capacity is desired, a double bed is secured on the left hand door 12 which is adjacent to the free end of the intermediate door, as indicated by dotted lines in Fig. 2. This permits the intermediate door to be swung into position shown in dotted lines in Fig. 2, to provide access to the double bed and permit its projecting portion to swing into the living room. This door may, if desired, be of sufficient width to permit entry into the closet while the double-bed is in position on the left-hand door.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. The combination with a wall-closet or recess, of a plurality of beds movable into 110

- said closet or recess, centrally pivoted horizontally swinging doors to which the beds are respectively and removably secured so they can be swung horizontally from the 5 closet into the adjacent room and an intermediate door between said centrally pivoted doors, the centrally pivoted doors being formed to serve as closures both when the beds are in the closet or recess and when they 10 are in the room, the intermediate door being operable so it can be opened or closed when the beds are in the closet or recess or in the room.
2. The combination with a wall-closet or 15 recess, of a plurality of beds movable into said closet or recess, centrally pivoted horizontally swinging doors to which the beds

are respectively and removably secured so they can be swung horizontally from the 20 closet into the adjacent room and an intermediate door between said centrally pivoted doors, and pivoted to swing on a point adjacent the end of one of the centrally pivoted doors, the centrally pivoted doors being formed to serve as closures both when the 25 beds are in the closet or recess and when they are in the room, the intermediate door being operable so it can be opened or closed when the beds are in the closet or recess or in the room. 30

Signed at New York, New York, this 10th day of July, 1924.

CHARLES C. WHITE.
